UNITED STATES PATENT OFFICE.

CHARLES R. VAN OSDEL, OF LA GRANGE, ASSIGNOR TO HIMSELF AND
GEORGE W. STRAIGHT, OF CHICAGO, ILLINOIS.

LUMBER-DRIER.

SPECIFICATION forming part of Letters Patent No. 363,704, dated May 24, 1887.

Application filed June 29, 1886. Serial No. 206,002. (No model.)

To all whom it may concern:

Be it known that I, CHARLES R. VAN OSDEL, residing at La Grange, in the county of Cook and State of Illinois, and a citizen of the 5 United States, have invented certain new and useful Improvements in Lumber-Driers, of which the following is a full description, reference being had to the accompanying drawings, in which—

10 Figure 1 is a vertical longitudinal section; Fig. 2, a cross-section on line $x-x$ of Fig. 1; Fig. 3, a cross-section on line $y-y$ of Fig. 1.

The object of this invention is to connect a condenser with that class of dry-kilns known 15 as "progressive driers" and to improve the construction and operation of this class of kilns or driers; and its nature consists in the several combinations of parts hereinafter described and claimed as new.

20 In the drawings, A indicates the drying chamber or space; B, the floor; C, the roof; D, the dome or end elevation; E, the condenser; F, water-receiver; F', trough; G H I, doors; J, posts or frame-work for elevating the door I; 25 K, lumber-trucks; L M, air-passages; N, heater; O, partition in air-space; $a b c$, cords with weights for counterbalancing the doors; d, a cross-board or frame, and e adjusting-roads.

30 The floor, walls, and roof of the kiln are made in any of the usual and well-known modes and of any suitable material. The drying space or chamber A may be adapted to the material to be dried, and it is advisable 35 to make it in such form in cross-section that a proper load upon the truck will nearly fill the space between the sides and the top. The floor is slightly inclined, as shown, so that the loaded cars will move of their own weight 40 toward the door I, through which the trucks are discharged when the lumber is dried.

This floor is provided with openings L and M for the passage and circulation of air, the hot air passing through slots or perforations at M of the heater N and the cool air descending 45 through the grated or open passage L into the air-space beneath the floor B.

The coil or heater N is made of steam-pipes in any well-known manner, except that it is 50 inclined to one side, as shown in Fig. 3, the better to get rid of the water of condensation.

The end at which the trucks enter is pro-

vided with an elevation or section, D, within which is placed a secondary door, H, and a condenser, E. This condenser is made of a 55 series of metal pipes arranged in sections or folds one above the other, as shown in Fig. 2, which may be arranged in a single line, as shown, or in two or more lines, as may be desired. This condenser is arranged within the 60 elevated space, so that the loaded trucks may pass beneath it, and so as to furnish a sufficient space for all of the air circulating to pass through the condenser. The bottom of the condenser is provided with a trough, F, which 65 is arranged to receive the water from the condenser E and to conduct it outside of the kiln. The condenser will also be so connected with a tank or otherwise arranged that a stream of cold water will flow through it and 70 keep it cool.

The door H divides the cooled or cold air space from the kiln and prevents an interior circulation, and also causes the colder air to pass through the opening or openings L, down 75 and beneath the floor or partition O. The doors G and I are ordinary doors common to that class of kilns which provide for the entrance and discharge of truck-loads of lumber or other material to be dried. The trucks K are 80 of the ordinary construction, and the floor is provided with rails or tramways, upon which the wheels run.

In the operation of filling and discharging the kiln, suitable trucks being provided, the 85 trucks are entered through the doorways G and H, and, after the kiln is once filled, as each car of dried lumber is discharged at the door I another is entered through the door G, thus keeping the greener lumber at the rear and 90 advancing the lumber as it dries, as in other progressive kilns.

In the operation of drying, the air is heated by the heater N and passes up between the space or spaces M into the drying-chamber, 95 and from thence it passes to the rear, through and around the lumber, until it reaches the end of the drying-chamber, where it passes up over the door H, then through the condenser E, where the surplus of its moisture is extracted, 100 then down in the chamber or passage between the doors G and H, through the openings L, and again into the space beneath the floor B or partition O. By this arrangement I am

enabled to thoroughly dry the contained lumber by substantially the same body of air thus put into circulation. As the air leaves the lumber it is surcharged with moisture, and, 5 coming in contact with the cold pipes of the condenser E, the surplus moisture is discharged and the air made sufficiently dry for returning it to the heater and drying-chamber. This is a very advantageous arrangement, and especially so in cold weather, as the air, after 10 passing the condenser, is not as cold as the exterior atmosphere, and therefore requires much less heating to bring it to the proper temperature for the best results in drying.

15 The partition-projection d causes the heated air to pass to the condenser at a point higher than the top of the door H and improves the uniformity of air currents or movements. It may be a cross-support for the trough F', or it 20 may form a part of it. The trough F' is made of or lined with pure sheet-lead, which is not affected by the wood acids, as is iron or tin, and does not warp or check, as wood is liable to do, and the frame-work F and partition d may be 25 lead lined or covered. It will be advisable to use this projection or partition even when the door H is placed on the other side of the condenser, as it may be if it is not carried too far away from the condenser, and this door may 30 be made in two parts hung on hinges when it is not desirable to carry the condenser high enough to furnish a space for it.

In order to prevent the air-currents from reversing, as they might do under the inclination 35 of the floor, I have provided a partition, O, which prevents this, as it makes the point of entry for the colder air lower than the discharge-opening for the heated air. This partition may be made in the form shown, or it 40 may be a simple vertical partition, and it may also be made adjustable by the adjusting- rods e, so as to make the point of entry for the cooled air higher or lower, and by placing a vertical cross-board at the lower end the floor- 45 ing above it may be dispensed with, except that between the door H and the openings L and that between the partition O and the heating-coil, and by extending the partition this part may be omitted.

50 In the ventilated or circulating kilns now in use the opening at the lower end of the kiln is short or narrow, so that, at the best, the heated air is only applied directly to one truck. In my kiln I make the opening M from twelve 55 to sixteen feet long and of the full width of the kiln, thus leaving the heated and expanded air to pass up in large volumes or quantities and apply itself to two or three trucks or car- loads with equal if not better results than 60 when applied to only one load or car.

By the constant action of expanding the air at one end of the kiln and contracting it at the other end I secure and maintain a rapid circulation of the air, and at the same time I 65 extract the surplus moisture, so that the surface of the lumber is not scalded, stained, or molded, and, as for the same body of lumber

or charge for the kiln I obtain the desirable result of drying in a diminishing moisture, the lumber is not checked or split, and it retains its bright and fresh appearance.

I have described my improvements as applied to a lumber-drier, but they may be applied to brick, vegetable, and other driers or kilns; and for the purpose of preventing the escape of the heated air and the disturbance of the circulation in the chamber an inclosed extension for discharging a car may be placed around the door I, with an end or side door, as may be most convenient.

I do not claim, broadly, the application of a condenser to a drying-kiln; but

What I claim as new, and desire to secure by Letters Patent, is—

1. In a drying-kiln, the combination of a 85 drying-chamber having an elevated space at one end, an elevated air-cooling chamber adjacent to and communicating with the elevated end of the drying-chamber, a condenser located in the upper part of said air-cooling 90 chamber, a door separating the lower parts of said chambers, but permitting them to communicate at the top, a space beneath said chambers communicating directly with each chamber through openings in its floor, and a 95 heater located in said space beneath the floor- openings of the drying-chamber, substantially as described.

2. In a drying-kiln, the combination, with a 100 drying-chamber, a cold-air chamber, and a space beneath the inclined floor of said chambers and communicating with each, of an adjustable partition located in said space to prevent a reverse circulation, substantially as described.

105 3. In a drying-kiln, the combination, with a drying-chamber, a cold-air chamber, said chambers communicating at the top, and a condenser located in the upper part of the cold-air chamber, of a door separating the 110 lower parts of said chambers and a partition, d, located above said door, substantially as described.

4. In a drying-kiln, the combination of the 115 drying-chamber A, having an elevated space at one end, the adjacent elevated air-cooling chamber D, door H, separating the lower parts of said chambers, but permitting them to communicate at top, the condenser E, located in the upper part of the cooling-chamber, a space 120 beneath the inclined floors of the drying and cooling chambers and communicating therewith through openings M L, a heater, N, located in said space beneath the openings that communicate with the drying-chamber, and an inclined partition, O, located in said space 125 near the bottom of the cooling-chamber to prevent a reverse circulation, substantially as described.
